HAROLD EDENBOROUGH, OF CHELSEA, LONDON, ENGLAND, ASSIGNOR TO DOUGLAS WISE DRIVER, OF ASHFORD HILL, NEAR NEWBERRY, BERKSHIRE, ENGLAND.

ENGINE-GOVERNING DEVICE.

Application filed September 30, 1925. Serial No. 59,651.

This invention relates to engine governors. The type of governor to which the invention relates is that in which the control of motive fluid supplied to the engine is effected by means of a hinged or pivoted reciprocating mass which, when the speed of the engine increases above the normal, contacts with a member, such as a pawl or pivoted rod, whereby the throttle or other governing valve of the engine is controlled through suitable mechanism. In governors of this type the mass is carried on a reciprocating part of the engine, such as the cross-head or air-pump lever, or is mounted upon a member which is adapted to be reciprocated from any suitable moving part of the engine, for example, from a rotary shaft by means of an eccentric or the like or from a reciprocating part by means of a lever, 20 connecting-rod or the like.

The object of the present invention is to provide an improved governor of the aforesaid type which is easily accessible for purposes of adjustment and regulation when the engine which it controls is in motion, is easily adaptable to existing engines and is efficient also in its control of the speed of the engine.

The improved governor, in accordance 30 with the present invention, comprises a base-plate, frame or the like adapted to be mounted on any suitable fixed structure, a member adapted to be reciprocated from the engine in guides on said frame, a mass pivoted on said reciprocating member, a 35 slidable member mounted on said base-plate adjacent to the reciprocating mass and a member which is pivoted on said slidable member and adapted to be positively engaged by the mass when the speed of the 40 engine increases above the normal and moved by it in the direction of the reciprocating motion and then automatically disengaged and to be again positively engaged 45 by the mass and automatically disengaged when the speed returns to normal.

If desired, means may also be provided whereby when a certain pre-determined speed is exceeded, the device is locked in 50 the position in which the supply of motive fluid is shut off.

According to one preferred form of construction of the invention, the reciprocating mass comprises a spring-controlled lever 55 which is pivoted on a sliding member which

is reciprocated from the engine shaft. An adjustable weight is mounted upon one end of the lever while the other end is provided with two claws or the like adjacent to the path to which there is mounted a movable 60 bar on which is pivoted a double trip member which is normally just clear of the said claws but, one end of which is engaged by one of the claws on the lever when the speed is increased, and the other end is engaged 65 by the other claw of the lever when the speed is again reduced to normal, so that the bar is moved upwards or downwards and thereby controls the supply of motive fluid by any suitable means. 70

The control of the supply of motive fluid to the engine may be effected either directly or indirectly, for example, through the piston of a relay cylinder. In the latter case the governor may, in accordance also with 75 the invention, operate means such as a four-way cock whereby fluid under pressure may be admitted to either side of the piston in the relay cylinder, the opposite side being at the same time put in communication with the 80 atmosphere. In this way, the power available for controlling the supply of motive fluid may be increased as desired and will depend upon the pressure of the fluid, for example, compressed air, which is admitted 85 to the relay cylinder and the area of the piston.

The governor may be driven either at engine speed or at any other suitable speed 90 by means of gearing, depending upon the speed of the engine. A suitable speed has been found to be about 70-100 reciprocations per minute.

A preferred embodiment of the invention is illustrated by way of example in the accompanying drawing, in which 95

Fig. 1 is a side elevation of the governor, partly in section and connected with a four-way cock for operating a relay cylinder 100 which is not illustrated.

Fig. 2 is a section on the line II-II of Fig. 1,

Fig. 3 a section on the line III-III of Fig. 1, and

Figs. 4 and 5 two sections showing the 105 four-way cock in its two alternative positions.

Referring to the drawing, the shoe-plate 1 is movable in the guides 2, 2, which are fixed by means of studs 4 to the base-plate 110

3, which is mounted on any suitable fixed structure. One of the guides 2 is adjustable, for example, in case of wear, by means of the screws 5. The shoe plate 1 can be reciprocated in the guides 2, 2 by means of an eccentric or connecting rod 6 which is coupled to a suitable rotating or reciprocating part of the engine. On the shoe-plate 1 there is mounted by means of the pivot 7 an escapement lever 8, one end of which is formed with two claws 9, 10 having a projecting stud or distance piece 23 midway between them while the other end is screw-threaded and provided with a counter-balance weight which is adjustable along the screw-thread 48. Below the lever 8 is fitted a screw-cap, comprising an outer tubular member 11, which is externally threaded and provided with a head 10' and locking-nut 12, and an inner tube 9' which is slidable in the tubular member 11 and fits over a spiral spring 13 enclosed by the said tubes 11 and 9'. The screw-cap is held in position below the lever 8 by means of a member 14 which is fixed to the shoe-plate 1 and provided with an internally threaded aperture into which the member 11 can be screwed and fixed in any desired position by means of the nut 12. The lever 8 rests with its bottom edge on the end of the tube 9'. The screw-cap and the position of the weight on the lever may be so adjusted that the latter will remain in its normal substantially horizontal position, but oscillating to a slight extent about its horizontal axis, for any predetermined speed of the engine. Adjacent to, but just clear of, the path of the claws 9, 10 there is arranged a vertical bar 15 which is movable up and down in guides 16 and 17 which are fixed to the base-plate 3. The bar 15 is provided at or near its centre with a recess 22 in which is pivoted a latch comprising a substantially vertical portion 18 having toothed or pointed ends 19 and 20 with which the claws 9 and 10 can respectively engage and a substantially horizontal extension 21 integral therewith which engages, with sufficient play to allow of slight oscillation, in the recess 22 in the bar 15. The extension 21 is pivoted, as illustrated in Fig. 2, about a pivot 24, the head of which lies in a recess in said extension and is prevented from rotating by means of a pin 25 which engages in a hole in the bar 15. The whole is secured by means of a plate 26, which is fixed by means of studs 27 above the extension 21 in a larger recess in the bar 15. The outer end of the pivot 24 is provided with a spring 28, adjustable by means of the nut 29, so as to cause side friction when the extension 21 is moved and retain the latch in any position in which it is placed or to prevent it from becoming prematurely operative through vibration or wear. The bar 15 is provided with stops 30 and 49 in order to limit its downward and upward movement. A spring-operated push-bolt 50 which engages in a recess 51 in the bar 15, when in its raised position, prevents the bar from prematurely moving downward by its own weight.

The stroke of the shoe-plate and the distance between the claws 9 and 10 of the lever and the upper and lower ends 19 and 20 of the latch are so arranged that when the bar 15 is in its normal lower position the stroke of the shoe-plate 1 is such that the lower claw 10 moves from just below the level of the lower end 20 to about the height of the upper end 19, and, when the bar 15 is in its upper position, the upper claw 9 moves from just above the level of the upper end 19 to about the level of the lower end 20.

The mode of operation is as follows:

The spring-cap 10' and the position of the counter-balance weight 12 are adjusted so as substantially to compensate the inertia of the weight at the predetermined normal speed at which the engine is to run, the lever 8 being slightly tilted upwards so that the top claw 9 bears lightly against, or is just clear of, the bar 15 and the bottom claw 10 is clear of the latch throughout its stroke at normal speed. The spring 28 is also adjusted so that the latch remains in any position in which it is placed owing to friction, and the latch is set so that the top end 19 is level with the face of the bar 15 or nearly so. A ribbon spring 31 may be provided, as shown in Fig. 1, in order to ensure that the latch remains in the position in which it is set, i. e. with the lower end 20 projecting from the bar.

As long as the speed of the engine remains normal the lever 8 oscillates slightly about its pivot 7 but not sufficiently to cause the lower claw 10 to engage the lower end 20 of the latch. When the speed of the engine increases above the normal the amplitude of the oscillations of the lever 8 increases, owing to the inertia of the weight overcoming the spring 13, until the bottom claw 10 is brought below the protruding end 20 of the latch and engages in it. The bar 15 is therefore drawn upwards and thereby operates means for controlling the supply of motive fluid to the engine. On the next down-stroke of the lever 8 the distance piece 23 hits the face of the lower half of the latch, which is still projecting, and thus moves the upper end 19 outwards but this end is again forced back level with the face of the bar 15, and remains in this position owing to the friction at the pivot and to the fact that the spring 31, if fitted, is not able entirely to overcome this friction, by the impact of the top claw 9 during the next up stroke, so that on the next down stroke the

claw 9 passes clear of the top end 19 of the latch. This action is repeated so long as the overspeed is maintained, and the bar therefore remains in the raised position and the motive fluid is cut off or partially cut off.

As the speed of the engine again returns to normal, the distance piece 23 on its down stroke again forces the upper end 19 of the latch outwards, in which position it remains since, at normal speeds, the impact of the claw 9 is not sufficient to force it back with the face of the bar 15. Consequently on the next stroke the claw 9 engages in the upper end 19 of the latch and moves the bar 15 downwards and thereby adjusts the means for controlling the supply of motive fluid to its original position.

The governor may be adjusted to suit varying speeds either by screwing the cap 20 containing the adjusting spring 13 upwards or downwards according as more or less tension of the spring is required, or by altering the position of the weight 12 on the lever 8 or by a combination of these 25 methods. Should there be any tendency for the governor to hunt, the spring 28 should be adjusted so as to produce the necessary friction.

The control of the supply of motive fluid 30 to the engine may be effected either directly, or indirectly through a relay, by any suitable means. Thus the bar 15 may be connected to the throttle valve. Or, as illustrated in Figs. 1, 4 and 5, the bar 15 may 35 operate a switch cock connected with a relay cylinder. In this case the bar 15 is connected by means of the rod 32 with the lever 33 of a four-way cock 34, of which the outlets 35, 36, 37 and 38 are connected respectively to the gland end of a relay cylinder, to the atmosphere, to a supply of fluid under pressure, for example, compressed air, and to the back end of the relay cylinder. The connections are such that when the 45 bar 15 is in its lower position, as illustrated in Fig. 1, the pipes 35 and 36 are in connection and also the pipes 37 and 38 so that the full force of the air pressure is applied to the back end of the relay cylinder, the pipe 50 to the other end of this cylinder being open to the atmosphere. When the bar 15 is moved upwards and turns the lever 33 the pipe to the back end of the cylinder is opened to the atmosphere providing escape 55 for the air there, and air pressure is admitted to the gland end of the cylinder through the pipe which was previously open to the atmosphere. The piston of the relay cylinder travels to the other end of the cylinder 60 thereby operating mechanism to cut off the supply of motive fluid.

A permanent locking-device whereby the lever 8, after having cut off the supply of motive fluid, is locked so that it does not 65 operate to admit the supply again when the

speed returns to normal, may also be provided. A suitable device is shown, by way of example, in Figs. 1 and 3, in which 39 is a plate which is pivoted at one end about a pivot 40 which is secured to the member 41, which is fixed to the shoe-plate 1 by means of bolts 42, so that the plate 39 lies in front of the lever 8. The plate 39 is provided with a recess 43 in which a collar-pin 44 is seated during the normal operation of 70 the governor. A spring 45 engages the collar on the pin 44 and is housed within a casing 46 which is carried by the member 41. The casing 46 is made in two parts which are relatively adjustable by means of screw- 75 threads for the purpose of altering the tension of the spring 45. The lever 8 is provided with a recess 47 lying directly behind the recess 43 in which the collar pin may engage. The pivoted plate 39 is normally 80 held in a substantially horizontal position by the collar pin engaging in the recess 43.

In operation, the spring 45 is adjusted so that the end of the collar pin 44 presses more or less tightly into the recess 43 in the plate 39, according to the predetermined speed at which the locking device is required to act. When this speed is exceeded the end of the collar pin is thrown out of engagement with the recess in the plate 39, owing to the inertia of the plate, and the plate turns about its pivot 40, thereby allowing the pin to enter the recess 47 in the lever 8 when the latter is in its shut position with the upper claw clear of the latch and so locking it in 100 the closed position, in which it remains until re-set by hand.

I claim:—

1. An engine governor of the inertia type including a reciprocating member, and a 105 mass pivoted thereon, characterized by a slidable member mounted adjacent said mass, and means pivotally supported on said slidable member for connecting the same to said mass for movement thereby when the 110 speed of the engine rises above and returns to normal.

2. The invention as set forth in claim 1, wherein said means comprises a member pivoted on said slidable member and having two portions thereof located adjacent the respective ends of the path of movement of said mass, said portions being alternately projected into the path of movement of said mass as said member turns about its pivot. 115 120

3. The invention as set forth in claim 1, wherein said means connects said mass and said slidable member for movement in one direction when the engine speed rises above normal, releases said slidable member from said mass at the end of the motion of the mass in the stated direction, and again connects the slidable member to said mass for movement in the opposite direction when the engine speed returns to normal. 125 130

4. An engine governor of the inertia type comprising a reciprocating member, a lever pivoted to said reciprocating member, a slide-
6 and a member pivoted to said slideable member and having portions thereof movable into the path of movement of said lever adjacent the respective ends thereof.
5. An engine governor of the type set forth comprising a member adapted to be reciprocated from the engine, a spring-con-
10 trolled lever pivoted on said reciprocating member and provided at one end with a weight and at the other end with two claws,
15 a slideable member mounted adjacent to said spring-controlled lever and a latch pivoted on said slideable member with which one or other of the said claws can engage.
6. An engine governor of the type set forth comprising a member adapted to be reciprocated from the engine, a spring-con-
20 trolled lever pivoted on said reciprocating member and provided at one end with an adjustable weight and at the other end with
25 two claws, a slideable member mounted adjacent to said spring-controlled lever and a latch pivoted on said slideable member with which one or other of the said claws can engage.
7. An engine governor of the type set forth comprising a base-plate adapted to be mounted on a stationary structure, a sliding member which is reciprocated from a moving part of the engine in guides on the said base-plate, a spring-controlled lever pivoted on said sliding member so as to be capable of slight oscillation and provided at one end with a weight and at the other end with two claws, a movable bar adjacent to the path of
30 said claws and a double latch member pivoted on said bar with which the said claws can positively engage when the speed of the engine varies.
8. An engine governor of the type set forth comprising a base-plate adapted to be mounted on a stationary structure, a sliding member which is reciprocated from a moving part of the engine in guides on the said base-plate, a lever controlled by an adjustable spring pivoted on said sliding member so as to be capable of slight oscillation and provided at one end with an adjustable weight and at the other end with two claws, a movable bar adjacent to the path of said claws and a double latch member pivoted on said bar with which the said claws can positively engage when the speed of the engine varies.
9. An engine governor of the type set forth comprising a member adapted to be reciprocated from the engine, a spring-con-
- 65 trolled lever pivoted on said reciprocating member, a slideable member mounted adjacent to said spring-controlled lever and a latch device pivoted on said slideable mem- 65 ber one end of which is movable into position to be positively engaged by the spring- controlled lever when the speed of the engine increases above the normal while the other end is positively engaged when the speed returns to normal, and means for introducing friction at the pivot of the trip device.
10. An engine governor of the type set forth comprising a member adapted to be reciprocated from the engine, a spring-con- 75 trolled lever pivoted on said reciprocating member and provided at one end with an adjustable weight and at the other end with two claws, a slideable member mounted ad- 80 jacent to said spring-controlled lever a latch device pivoted on said slideable member with which one or other of the said claws can engage, and means for holding one end of the latch device away from the face of the 85 slideable member.
11. The invention as set forth in claim 1, in combination with means for locking the governor in off position when a pre-
90 determined speed has been exceeded.
12. An engine governor of the type set forth comprising a base-plate adapted to be mounted on a stationary structure, a sliding member which is reciprocated from a moving part of the engine in guides on the said base-plate, a spring-controlled lever pivoted on said sliding member and provided at one end with a weight and at the other end with two claws, a movable bar adjacent to the path of said claws, a double latch member 95 pivoted on said bar with which the said claws can positively engage, and means for locking the governor in the off position.
13. The invention as set forth in claim 1, in combination with a four-way cock and 105 means connecting said slideable member therewith.
14. An engine governor of the type set forth comprising a base-plate adapted to be mounted on a stationary structure, a sliding member which is reciprocated from a moving part of the engine in guides on the said base-plate, a spring-controlled lever pivoted on said sliding member and pro- 110 vided at one end with a weight and at the other end with two claws, a movable bar adjacent to the path of said claws, a double latch member pivoted on said bar with which the said claws can positively engage, a four way cock and means connecting said 115 sliding member therewith.

HAROLD EDENBOROUGH.
